COPPER SWEETENING HYDROCARBON OILS

Davis Read, Jr., and Wayne L. Benedict, Chicago,
Ill., assignors to Universal Oil Products Com-
pany, Chicago, Ill., a corporation of Delaware

No Drawing. Original application August 18,
1939, Serial No. 290,846. Divided and this ap-
plication May 31, 1940, Serial No. 338,224

2 Claims. (CL 252—189)

This invention, which is a division of our co-pending application Serial No. 290,846, filed August 18, 1939, relates to a method of manufacturing an improved treating reagent useful for improving the odor and stability of hydrocarbon distillates in general and particularly those boiling within the gasoline boiling range. The hydrocarbon distillates which may be treated according to the present invention may be obtained by the straight run distillate or by the cracking of higher boiling hydrocarbon oils. The source of such oils may be coal tar oil, shale oil and the like, but is usually from crude petroleum oil and similar sources.

Practically all petroleum distillates require some form of refining in order to produce a marketable product. This is particularly true of gasoline which requires some form of treatment to improve the odor, prevent deterioration in storage, eliminate corrosion of metal parts with which the gasoline is likely to come in contact, etc.

Many distillates require only a sweetening treatment with or without the addition of inhibitors to improve storage stability. Among the processes practiced for this purpose is the sodium plumbite process, the hypo-chlorite process and various modifications of the so-called copper sweetening process. It is with improvements in the latter that the present invention is concerned.

In one specific embodiment the present invention comprises a method for manufacturing a copper sweetening reagent which comprises mixing a heated porous filler such as pumice, fuller's earth, firebrick and the like with a heated solution of copper sulfate and an alkalinous chloride wherein the weight ratio of copper sulfate to said chloride is within the range of approximately 50:50 and 67:33 under conditions such that a major portion of the water contained in said solution is evaporated, thereby producing an active copper sweetening agent.

The impregnation of relatively inert fillers with copper salts to produce sweetening reagents has been practiced previously. However, we have discovered when using fillers impregnated with mixtures of copper sulfate and an alkalinous chloride that the weight ratio of the copper sulfate to said chloride is critical if the best results are to be obtained. The critical limits of these weight ratios are within the approximate values of 50 parts copper sulfate to 50 parts alkalinous chloride, and 67 parts copper sulfate to 33 parts alkalinous chloride. In certain cases when using 55

reagents outside this range, little or no sweetening can be obtained with the reagent, while in other cases the reagent sweetens but is found to have limited life. In still other instances, the 5 reagent sweetens the distillate but is found to produce a product of inferior quality.

The term alkalinous chloride is defined as including the chlorides of alkali or alkaline earth metal chlorides as well as of the hypothetical 10 metal ammonium. Equivalent halides such as the bromide may also be used.

The reagent of the present invention is prepared by the impregnation of a spacing agent or 15 filler such as pumice or fuller's earth or other porous, relatively inert materials, with the chemicals mentioned. The impregnation is suitably carried out by the following method: The filler, such as 6-20 mesh pumice, is heated to a 20 temperature of approximately 250-400° F., and preferably to about 350° F. The copper sulfate and alkalinous chloride, such as ammonium chloride, in the desired proportions are dissolved in water at a temperature of approximately 150-200° F. The strength of the solution should 25 be such that no precipitation of salt occurs at the temperature used but should be as nearly saturated with the mixed salts as possible. The hot solution and the hot filler are rapidly and intimately and uniformly mixed by any suitable 30 method such as spraying the solution on the filler under conditions such that rapid evaporation of the water takes place. A blast of air may be passed over the heated mixture in order to carry away water vapor as it is evolved and to 35 dry the reagent to the desired point. The reagent should contain approximately 5-20% of moisture when finished. The quantity of salts deposited on the filler may vary considerably. Normally, there should be sufficient salt so that the total 40 reaction mixture analyzes 1-5% copper. Satisfactory reagents have been made containing between 2 and 4 per cent of copper when using the ratios of copper sulfate to alkalinous chloride as stated herein.

The reagents of this invention have the advantage that they are uniform in particle size and composition; the particle size of the granules can be chosen so as to produce uniform distribution and contact of hydrocarbon during the sweetening step thus allowing more careful control of the operation; and sweetened distillates of improved quality are produced from the process in which the reagents are used.

The sweetening process in which the reagents are used normally comprises contacting hydro-

carbon distillate mixed with air with the copper sweetening reagent at temperatures of approximately 60-120° F., the preferred range being 70-90° F. The reagent is normally used in granular form but may be used as a powder or slurry in some cases. The copper-sweetening step is normally followed by a secondary treating step in which impurities present in the gasoline as a result of the copper-sweetening step are removed. In certain instances, such as when sweetening some straight-run gasolines, this secondary step may be dispensed with, but is usually a necessary part of the process. The reagents used for this purpose include alkali metal sulfides, zinc sulfide, iron sulfide, etc. When using the present reagent in the copper sweetening process, the use of the secondary treating step is intended where such treatment is necessary. The residual air from the primary treating step is preferably released prior to the secondary step.

The following examples are given to illustrate the applicability of the process but should not be construed as limiting it to the exact conditions given therein.

Example 1.—A reagent was prepared by heating 6-20 mesh pumice at a temperature of 350° F., separately heating copper sulfate and ammonium chloride with just enough water to completely dissolve the mixture at a temperature of 200° F., the salts being present in the ratio of 66.7 parts of copper sulfate to 33.3 parts of ammonium chloride by weight. The hot solution was sprayed onto the hot pumice in such a manner that a uniform coating was obtained. The water was permitted to evaporate under these conditions. It was found that the final reagent contained the equivalent of 2.05% of copper and

14.2% of water. This reagent was found to be satisfactory for sweetening a Mid-Continent cracked gasoline. More than 12,000 barrels of sweetened gasoline per ton of reagent was obtained.

Example 2.—The reagent was prepared in a similar manner to that described in Example 1, except that the weight ratio of copper sulfate to ammonium chloride was 50:50. This reagent satisfactorily sweetened the gasoline. A yield of more than 15,000 barrels of gasoline per ton of sweetening reagent was obtained.

Reagents prepared in a similar manner, but wherein the weight ratios of copper sulfate to ammonium chloride were 40:60, 37.5:62.7 and 70:30, were unsatisfactory as sweetening reagents. The maximum quantity of gasoline produced by any one of these reagents was approximately 200 barrels per ton. The reagent could not be satisfactorily regenerated following this treatment.

We claim as our invention:

1. A process for manufacturing an oil refining agent comprising heating a granular carrier to a temperature within the range of approximately 250-400° F., mixing with said carrier a solution of copper sulfate and an alkalinous chloride, the weight ratio of copper sulfate to said chloride being within the limits of approximately 50:50 and 67:33, said solution being heated to a temperature within the range of approximately 150-250° F. and allowing a portion of the excess water to evaporate.

2. The process of claim 1 wherein the alkalinous chloride is ammonium chloride.
